UNITED STATES PATENT OFFICE.

HENRY H. BLAKE, OF PITTSBURGH, PENNSYLVANIA, ASSIGNOR TO BLAKE CRUSHER AND PULVERIZER COMPANY, OF PITTSBURGH, PENNSYLVANIA, A CORPORATION OF PENNSYLVANIA.

APPARATUS FOR DISTRIBUTING PULVERIZED FUEL.

1,104,404.

Specification of Letters Patent. Patented July 21, 1914.

Application filed July 21, 1911, Serial No. 639,756. Renewed December 8, 1913. Serial No. 805,431.

To all whom it may concern:

Be it known that I, HENRY H. BLAKE, a citizen of the United States, and residing in the city of Pittsburgh, in the county of Allegheny and State of Pennsylvania, have invented or discovered new and useful Improvements in Apparatus for Distributing Pulverized Fuel, of which the following is a specification.

10 My invention relates to new and useful improvements in apparatus for the supply of pulverized fuel to a furnace or furnaces from a source of supply such as a pulverizer or pulverizers.

15 Generally speaking, it consists of one or more distributor located above and in front of the furnace and of means for supplying the pulverized fuel thereto from the source of supply.

20 The form of distributor shown consists of a hollow body having a closed rounded or dome shaped top and preferably increasing in width and decreasing in depth toward the discharge slot or openings at its bottom through which the fuel is discharged into the combustion chamber of the furnace. The fuel is introduced into the distributor at a point near its top and in an upwardly direction so that it is reverberated by the top 25 of the distributor downwardly through its body to the discharge slot or openings at its bottom. The reverberation of the fuel accomplishes its even distribution so that the full extent of said slot or openings is uniformly fed. The distributor is preferably made of two portions; a base portion mounted on the top of the furnace, and a body portion removably mounted on the base.

30 The pipe which supplies fuel to the distributor communicates with the body portion at an acute angle from below and is preferably attached to said body, being removably attached to or mounted on the end of a fuel supply pipe.

35 Where two adjacent furnaces are fitted with my distributors, I prefer to have their respective pipes enter the distributor from adjacent sides and the two pipes communicating with a common supply pipe which is provided for that purpose with a duplex end. Valves are provided in said duplex end to control the admission of fuel to either distributor, as need be. The supply pipe is preferably provided with a duplex lower

end so that it may be connected with a pair 55 of pulverizers or other sources of supply to insure a continuous supply of fuel. Valves are provided in said duplex lower end so that either or both pulverizers may be cut out when not needed.

60 In the accompanying drawings, Figure 1 is an elevation showing the installation of my invention on two adjacent boiler furnaces, and Fig. 2 is a vertical section along the line II-II in Fig. 1.

65 The following is a detailed description of the drawings.

A—A represents the front walls of a pair of furnaces, illustrated as boiler furnaces, and B—B are the doors through which access may be had, when required, to the boiler tubes. In front of and above each furnace a distributor is installed for the supply of fuel to the combustion chamber thereof. The lower portion of the distributor is composed of a base C supported on top of the furnace by any convenient means, such as end brackets 1—1. The base C is an open top box of steel plate of proper shape to follow the contour of the furnace arch D. 70 The bottom of base C is preferably provided with a slot 2 extending substantially across the width of the furnace and communicating with the interior thereof, through a slot 3 located between the top of the front wall A and the arch D. The rear wall of base C rests against a lip 4 on the face of the arch which spaces the base away from the body of the arch and thus protects it from the extreme heat thereof. The lower front wall of 75 the base C is composed of a plurality of damper plates 5—5 swung from the upper front wall and extending down into said slot 3. The position of said plates 5—5 is controlled by movable bricks 6—6 which 80 form the top course of the front wall A and by means of which the width of the slot is regulated either for its full length or for any desired portion thereof, thus adjusting the quantity of fuel admitted to the furnace. 85

90 7—7 represents a series of doors in the upper front wall of base C by means of which access may be had with a tool to loosen any clogging that may occur in the distributor or in its discharge slot. The top 95 edge of base C is preferably horizontal and provided with a flanged shoulder 8 in which is placed a compressible gasket 9.

The body E of the distributor is preferably made of sheet metal with a rounded or dome shaped top and preferably decreasing depth and increasing width toward its bottom edge which is adapted to fit down into the shoulder 8 and rest upon the gasket 9. In the upper portion of the body E and in one side of the same, is a port 10 which communicates with an upwardly extending fuel pipe 11 which joins the body E at an acute angle and is preferably attached thereto. The lower end of pipe 11 fits into and rests upon the flanged shoulder 12 on the top of the supply pipe 13, similarly to the manner in which the body E rests upon the top of base C, so that the body C with its attached pipe 11 may be lifted from place when desired, as, for instance, for repairs or to permit access to the door B.

14 is a ring in the top of body E to facilitate its removal or replacement. Where, as in the drawings, adjacent furnaces are provided with my distributors, I locate their pipes 11—11 on their adjacent sides and mount the lower ends of said pipes on the flanged shoulders 12—12 of the duplex end of the supply pipe 13. Valves 15—15 are provided for the duplex upper end of pipe 13 so that the fuel may be cut off or admitted to either distributor at pleasure, or the amount of fuel admitted thereto regulated. I prefer to make the lower end of pipe 13 also duplex and connected with the discharge pipes 16—16 of the pair of pulverizers F—F, or other source of pulverized fuel supply. Valves 17—17 are provided in the lower duplex end of pipe 13 so that either pulverizer may be cut off as required. When one pulverizer becomes disabled, the other may be put into commission, so that the fuel supply to the furnaces is continuous.

The operation of my invention is as follows. The valve 17 of one or both of the pulverizers is opened and fuel admitted to the pipe 13 whence it passes through the pipe or pipes 11 to the distributor or distributors, as indicated by the adjustment of the valves. Entering the distributor, the fuel is reverberated by the rounded top of the same and passes down through the body uniformly distributed throughout the extent of the same and through the slot 2 into the furnace. The quantity of fuel admitted through the slot 2 or any portion thereof may be adjusted by means of the dampers 5—5, and the amount of the fuel admitted to the distributor from the supply pipe 13 by means of the valve 15.

What I desire to claim is—

60 1. In apparatus for the purpose de-

scribed, the combination of a furnace having a vertical opening in the top thereof, a distributor having a closed rounded top placed in a vertical position above the furnace and communicating at its bottom with 65 said opening, and a fuel supply pipe leading upwardly into the side of the distributor which discharges the fuel against the rounded top of the distributor by which said fuel is reverberated downwardly into the 70 furnace.

2. In apparatus for the purpose described, the combination of a furnace having a vertical opening in the top thereof, a distributor base mounted on said furnace 75 and communicating with said opening, a distributor body having a closed rounded top mounted vertically on said base, a main fuel supply pipe adjacent to said furnace, and a second fuel supply pipe mounted on said 80 main pipe and leading upwardly into said body which introduces the fuel upwardly against said rounded top by which said fuel is reverberated downwardly through said base into the furnace.

3. In apparatus for the purpose described, the combination of a plurality of furnaces provided with vertical openings in their tops, a distributor having a closed rounded top mounted vertically on each of 90 said furnaces and communicating with said openings, a main fuel supply pipe communicating with the source of fuel supply adjacent to said furnaces, and branch pipes leading from said main pipe upwardly into 95 said distributors by which said fuel is introduced against said rounded tops by which said fuel is reverberated downwardly through said distributors into the furnaces.

4. In apparatus for the purpose described, 100 the combination of a plurality of furnaces provided with vertical openings in their tops, a distributor having a closed rounded top removably mounted in a vertical position on top of each furnace and communicating 105 with the opening thereof, a main fuel supply pipe communicating with the source of fuel supply adjacent to said furnaces, and branch pipes removably mounted on said 110 main pipe and leading upwardly into said distributors by which said fuel is introduced against the rounded tops by which said fuel is reverberated downwardly through said distributors into the furnaces.

Signed at Pittsburgh, Pa., this 20th day of July 1911.

HENRY H. BLAKE.
